HOSE SUPPORTER

Everett H. Reed, Detroit, Mich., assignor of one-half to Ruth M. Olds, Detroit, Mich.

Application May 31, 1934, Serial No. 728,227
Renewed March 9, 1938

3 Claims. (Cl. 241—6)

This invention relates to hose supporters, and has for its principal object to provide a new and improved construction for such devices whereby greater comfort for the wearer is assured and, of even more importance, pressure is avoided on any part of the wearer's leg where the blood carrying canals, i. e. veins or arteries, are sufficiently close to the surface to be affected by superficial pressure to such an extent as would result in retarding or checking the circulation. The usual type of men's garters consisting of an elastic band worn just above the calf of the leg exerts considerable superficial pressure that tends to retard or check the blood's circulation through the sub-surface canals, so that in many cases serious varicose conditions are brought about.

The present invention has for its object to provide a man's hose supporter which will maintain the wearer's socks in a neat, fully extended, smooth condition without producing any objectionable or harmful pressure on the wearer's leg, and which, moreover, will have marked advantages from the standpoint of ease and comfort for the wearer.

The above and other objects will appear more fully from the following, more detailed description, and by reference to the accompanying drawing forming a part hereof, wherein a preferred embodiment of the invention is illustrated, and wherein Fig. 1 is a front elevation showing the manner in which the hose supporter is adapted to be worn; the figure showing in dotted lines the outline of a sock and the manner in which it is supported;

Fig. 2 is a central, longitudinal section on an enlarged scale through the hose supporter clasp, and;

Fig. 3 is a section through the elastic anklet and supporting member.

Fig. 4 is a front elevation of a modified form of the hose supporting clasp and Figs. 5 and 6 are sections on the lines 5—5 and 6—6 of Fig. 4.

As shown in the figures the numeral 10 indicates a vertically extending supporting member preferably constructed of a thin sheet of substantially rigid material such as Celluloid, or other suitably transparent or flesh colored material. The term rigid, employed to describe the characteristic of the member 10, is however used in a relative sense to distinguish from material such as the usual elastic webbing commonly employed for hose supporters or garters, the member 10 being made from a relatively thin plate of material, has sufficient lateral flexibility to enable it to conform and lie closely adjacent to the wearer's leg, but the material has sufficient rigidity to remain in an upright vertical position and withstand the pull placed upon it in supporting a sock.

At its lower end the member 10 terminates in

an enlarged end 10a, which, as clearly shown in Fig. 3, is provided with a small aperture 11 adapted to receive the hooked end of a small, preferably metallic, hook 12. Suitably secured to a transverse slot 13 in the hook 12 is one end 5 of an elastic anklet 14, the other end of the anklet 14 is passed through a pair of spaced slots 15—16 provided in the enlarged end 10a in the manner shown in Fig. 3.

The way in which the anklet is passed through the slots 15—16 enables the size of the anklet to be adjusted in a manner that will be readily understood. The anklet is preferably made long enough so that the free end 14a thereof will project beyond the slot 16 far enough to extend 15 under the end of the hook 12 and to serve as a shield between said hook and the skin of the wearer, thereby preventing contact of any metal with the wearer's skin.

At its upper end the member 10 has slidably secured thereto a clasp 17 preferably made of spring metal suitably plated or otherwise treated to prevent oxidation or rusting thereof. The clasp 17 comprises a main body portion 17a having a pair of ribs or bars 17b struck out therefrom; the spacing of the bars 17b from the main body portion 17a of the clasp being such as to provide a guideway or slideway into which the vertical supporting member 10 is adapted to fit with a neat sliding fit. The clasp 17 also includes a spring clamping finger 17c which is bent downwardly and terminates at its lower end in an outwardly projecting nib 17d. Immediately adjacent to the nib 17d the finger 17c is provided with a small transverse rib 17e which is in alignment with the slot formed in the body 17a of the clasp by the striking out therefrom of the lowest rib 17b.

The inherent elasticity of the spring finger 17c causes the inner face of the rib 17e to press tightly against the front face of the vertical member 10, thereby to hold the hose supporting clasp in adjusted position along the member 10. As will be seen from Fig. 2 the outwardly projecting nib 17d of the clasp provides means for releasing 45 the pressure of the spring finger or tongue 17c upon the vertical member 10.

The manner in which the device is used is as follows:

The anklet 14 is adjusted to the proper size by sliding it through the slots 15—16 and so that it will fit neatly upon the wearer's leg just above the ankle joint so that the enlarged rounded end 10a of the member 10 fits into sulci formed by the tendon of Achilles either on the inside or outside of said tendon at the discretion of the wearer. It is not necessary, however, to adjust the anklet so that any appreciable pressure is exerted on the anklet, in fact, it is preferable to avoid such pressure. The anklet 14 having been 60

adjusted to the proper size, it is placed upon the wearer's leg just above the ankle and the hook 12 is engaged within the eyelet or aperture 11, the vertical member 10 preferably being placed to extend upwardly along the wearer's leg. The hose or sock 18 is then donned and the clasp 17 is adjusted vertically on the member 10 in a proper position to hold the sock fully extended. The upper end of the sock is then engaged under the spring finger 17^c which may be accomplished merely by pushing the end of the sock under the nib 17^d until it is engaged by the rib 17^e and clamped between said rib and the member 10. If desired the insertion of the sock into the clasp 15 may be facilitated by placing the finger under the nib 17^d and pulling the spring finger outwardly in a manner that will be readily understood.

After the sock has been engaged under the spring finger 17^c it will be noted that the material of the sock is pressed by the rib 17^e through the slot adjacent the rib 17^b into engagement with the upright 10, the textile material of the sock serving by its frictional contact with the member 10, to prevent longitudinal movement of said member along the vertical support.

The hose supporting clasp in modified form shown in Figs. 4 to 6 inclusive, is somewhat simpler from the standpoint of manufacture than that shown in Figs. 1 to 3. The modified clasp, indicated generally by the reference character 170 has a spring tongue 170^c which terminates in a projecting nib 170^d. A short distance from the extremity of the nib 170^d the spring tongue 35 170^c has formed therein a circular depression 170^e arranged in alignment with an aperture 170^f and through which aperture the depression 170^e serves to press the textile material of the hose into engagement with the upright 10, thereby to assist in holding the hose supporting 40 clasp in vertical adjusted position. The clasp 170 is slidably mounted for vertical adjustment on the upright 10 in a pair of opposed guideways formed by side flange portions 170^b, as shown 45 most clearly in Fig. 6 of the drawing.

As will be seen from the foregoing, a hose supporter constructed in accordance with the principles of the present invention entirely avoids the use of any tight elastic bands such as characterize the usual men's garters that are worn just above the calf of the leg at a point where there are numerous veins close to the surface and which contribute largely to serious varicose conditions. The present invention is also to be distinguished from hose supporters of the type having a rigid upright but wherein the lower end thereof is extended down into the shoe and around under the sole of the foot, the latter type of construction being impractical because of the 50 discomfort caused to the wearer and the tendency towards producing objectionable callus and irritation. Also such supporters necessitate the provision of a jointed member to compensate for movement of the ankle. With a hose 55 supporter constructed in accordance with the present invention, as hereinbefore stated, it is not necessary to adjust the anklet so that it exerts any appreciable pressure, but even if it is adjusted so that it clasps the wearer's leg rather 60 snugly, the veins in the locality immediately above the ankle joint are primarily deep rather

than superficial and consequently are not subject to constriction by positive surface pressure as they are in the region of the calf.

A hose supporter constructed in accordance with the present invention gives remarkable 5 comfort when in use, the absence of any tight constricting bands about the wearer's leg being quite apparent. At the same time the socks may be pulled up as tightly as the wearer desires; the upright member 10 being sufficiently rigid to 10 hold the sock fully extended and the clasp 17 remaining in its adjusted position without sliding. The clasp 17 can be readily adjusted as desired by merely exerting sufficient pressure to cause it to slide along said member.

The upright member 10, as hereinbefore stated, is preferably made of Celluloid which has a very low heat conductivity and due to its non-porous properties and glossy surface will not only remain in a clean sanitary condition, 20 but can be readily cleansed whenever it is desirable. As the upright may therefore be used indefinitely, the only part of the device which will need to be renewed from time to time is the relatively inexpensive small elastic anklet.

Although the anklet 14 has been shown and described as comprising a single piece of elastic material, such as webbing, it will be understood that it is within the principle of the present invention to construct the anklet partially of elastic material and partially of any suitable non-elastic material.

While I have described a preferred example of my invention, that has proven highly practical and successful in actual use, it will be understood that many variations, changes and modifications thereof may be resorted to without departing from the principles of the invention.

I claim:

1. A hose supporter comprising a thin plate-like, substantially inelastic, vertical member provided at the lower end thereof with anklet attaching means, an elastic anklet adjustably secured to said means, and a hosiery clasp slidably secured to said vertical member for vertical adjustment thereon, said clasp including a spring finger, the free end of which engages said member with a yielding pressure to hold said clasp in its vertically adjusted position.

2. In a hose supporter an adjustable anklet attached to encircle the wearer's ankle between the calf and the ankle joint, an upright substantially inelastic vertical supporting member secured to said anklet, means for adjusting the size of said anklet and means for detachably engaging one end thereof directly with said supporting member and a hose supporting clasp slidably adjustable along said supporting member, said clasp being provided with spring means for clamping the upper end of a hose to be supported in extended position by said vertical supporting member.

3. A hose supporter comprising a vertically extending member, an adjustable strap secured at one end to the bottom of said vertically extending member and detachably secured at the other end directly to the bottom of said member and a hose clamp slidably and adjustably mounted on said vertical member.
